COMBINED FILTER HOUSING AND CAP

Marcel Clarence Sicard, Cheshire, Conn., assignor to
The Cuno Engineering Corporation, Meriden, Conn.,
a corporation of Connecticut

Filed Mar. 28, 1958, Ser. No. 50,216

Term of patent 14 years

(Cl. D46—1)

FIG. 1.

FIG. 2.

FIG. 3.

Figure 1 is a front elevational view of a combined filter housing and cap embodying my new design;

Figure 2 is an end elevational view thereof; and

Figure 3 is a top plan view thereof.

The rear elevational view and the end elevational view not shown on the drawing are substantially similar to the front and end elevational views illustrated respectively in Figures 1 and 2.

I claim:

The ornamental design for a combined filter housing and cap, as shown and described.
